US00D802560S

(12) **United States Design Patent** (10) **Patent No.:** **US D802,560 S**
(45) **Date of Patent:** **** Nov. 14, 2017**

(54) **SOUND DEVICE**

(71) Applicant: **Creative Technology Ltd**, Singapore (SG)

(72) Inventor: **Shintaro Kitazawa**, Singapore (SG)

(73) Assignee: **CREATIVE TECHNOLOGY LTD**, Singapore (SG)

(**) Term: **15 Years**

(21) Appl. No.: **29/568,398**

(22) Filed: **Jun. 17, 2016**

(30) **Foreign Application Priority Data**

Dec. 18, 2015 (SG) 30201501880X

(57) **CLAIM**

The ornamental design for a sound device, substantially as shown and described.

DESCRIPTION

FIG. 1 is a front top right side perspective view of a sound device showing our new design;

FIG. 2 is a rear top left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines for the speaker drivers/grills in FIG. 1, FIG. 2, FIG. 3, FIG. 5, FIG. 6, FIG. 7, and FIG. 8 show unclaimed subject matter only and form no part of the claimed design.

1 Claim, 8 Drawing Sheets
